UNITED STATES PATENT OFFICE.

HENRY C. ZENKE, OF NEW YORK, N. Y.

BURNER.

SPECIFICATION forming part of Letters Patent No. 701,123, dated May 27, 1902.

Application filed March 8, 1901. Serial No. 50,338. (No model.)

To all whom it may concern:

Be it known that I, HENRY C. ZENKE, a citizen of the United States, and a resident of the city of New York, borough of the Bronx, in 5 the county and State of New York, have invented a new and Improved Burner, of which the following is a full, clear, and exact description.

The invention relates to linotype and other 10 machines in which a pot containing molten metal is employed.

The object of the invention is to provide a 15 new and improved burner which is simple and durable in construction and arranged to heat the pot and keep the contents thereof in a molten state to insure proper pouring of the metal into a mold or other part.

The invention consists of novel features 20 and parts and combinations of the same, as will be fully described hereinafter and then pointed out in the claims.

A practical embodiment of the invention is 25 represented in the accompanying drawings, forming a part of this specification, in which similar characters of reference indicate corresponding parts in all the views.

Figure 1 is a side elevation of the improvement as applied to a linotype-pot, the latter being shown in section. Fig. 2 is a trans- 30 verse section of the same. Fig. 3 is an enlarged sectional side elevation of the improvement on the line 3 3 in Fig. 4. Fig. 4 is a plan view of the same, and Fig. 5 is an inverted plan view of the main tip.

In burners for linotype melting-pots as 35 heretofore constructed reliance was had on the pressure of the gas to draw sufficient air into the mixing-chamber to form a proper mixture that would burn with a blue flame at 40 the tip of the burner; but as soon as the pot was heated to the desired degree and the operator or an automatic device partly shut off the gas then very little if any air was drawn into the mixing-chamber by the gas, and im- 45 proper mixing of the gas and a consequent poor flame at the tip was the result, producing thereby insufficient heat to keep the metal in the pot in proper condition for pouring it into the mold. In order to avoid this and 50 supply the necessary air for combustion, I employ an air-inlet for the mixing-chamber

and an independent inlet for the combustion-chamber under the pot to insure a perfect burning of the gas and a consequent proper heating of the pot at all times, no matter 55 whether the gas is fully or only partly turned on. In order to do this, the supply of air for the mixing-chamber and the combustion-chamber is so divided that the air will be drawn into the mixing-chamber and to the tip 60 whether the gas-pressure is wholly or partly turned on, thus insuring a steady supply of air for proper combustion irrespective of the gas-supply. Furthermore, provision is made for any metal that may leak out of the pot to 65 pass at once out of the burner without danger of clogging the burner, as is so frequently the case with burners heretofore constructed.

The pot on which the burner is applied is provided with the usual casing A, in which is 70 set a crucible A', having a pouring side A², and a cylinder A³, in which reciprocates a piston A⁴ for forcing the molten metal through a spout into a mold in the usual manner. On the under side of the casing A are formed de- 75 pending lugs A⁵, engaged by springs B, engaging corresponding lugs C' on the under side of the top plate C of the burner and holding the latter spring-supported on the under side of the pot, as is plainly shown in 80 Figs. 1 and 2. The top plate C of the burner is provided with an annular upwardly-extending rim C², abutting against the under side of the bottom of the casing A, around the central opening A⁶ thereof, as is plainly shown 85 in the drawings.

The mixing-chamber D is fastened to the under side of the top plate C by a suitable screw E, the upper end of the mixing-chamber fitting into a depending flange C³, integral with 90 the under side of the top plate C, as shown in Fig. 3. The lower end D' of the mixing-chamber opens to the atmosphere, and in the side of the mixing-chamber is a gas-inlet D², in which screws or fits a tip F, coupled to a 95 tube F', connected with a suitable gas-supply pipe. (See Fig. 1.) The top of the mixing-chamber D is connected by apertures C⁴ with the interior of a burner-tip G, preferably of the shape shown in Fig. 5, and formed 100 with a depending flange G', having notches G² in the under side, as plainly indicated in

Figs. 3 and 5. This tip G is secured to the top plate C by a screw H, and said tip extends up into the central opening A⁶ in the bottom of the casing A, as shown in Figs. 1 5 and 2.

Now it is evident that when the gas is turned on it rushes through the gas-inlet D² into the mixing-chamber, and thereby draws air through the lower end D' into said mixing-chamber to form with the gas a combustible mixture. This mixture passes through the opening C⁴ into the tip G and is burned upon issuing through the notches G² on the top plate C within a heating or combustion chamber formed between the top plate C and the under side of the crucible within the casing A, as will be readily understood by reference to Fig. 1.

In order to insure a complete combustion, 20 the top plate C outside of the tip G and the mixing-chamber D is formed with air-inlets C⁵, so that air can pass directly into the combustion-chamber and insure proper burning of the mixture, no matter whether the gas is turned on fully or only partly.

An auxiliary tip I in the form of a tube extends upward from one side of the mixing-chamber D and reaches within a short distance of the under side of the spout A², so 30 that part of the mixture of gas and air in the mixing-chamber can pass up said tube and auxiliary tip and be burned at the upper end thereof under the spout A², so as to heat the same and keep the metal contained therein 35 always in a proper molten condition. The combustion-chamber extends under the crucible A' and under the spout A² to connect with the usual chimney A⁷ for carrying off the products of combustion.

40 By the arrangement described an air-supply independent of that going to the mixing-chamber is had for the combustion-chamber, so that no matter how strong the pressure of gas in the mixing-chamber at the tip F the mixture will always be properly formed within the mixing-chamber, and a proper burning of this mixture, no matter how weak, will always be had at the tips G and I, owing to the air passing through the apertures C⁵ into the 45 combustion-chamber and causing a bright burning of the gas mixture at the tip G, and thereby drawing air into the mixing-chamber D at the inlet D' to insure a proper mixture of air and gas in the mixing-chamber no 50 matter how weak the pressure of the gas may be. It will be understood from the foregoing that the supply of air is divided, and the air-inlets C⁵ and D' are so proportioned as to accomplish the desired result.

60 By having the spring-supports for the burner the rim C² of the top plate is always held in proper contact with the under side of the casing A; but the burner can be readily detached at any time by disconnecting the 65 springs from the lugs A⁵. In case the crucible A' leaks then the molten metal dropping

upon the top plate C can readily pass through the apertures C⁵ and out of the burner without clogging the same.

Although I have shown and described my 70 burner as for heating metal in a pot, it is evident that it may be used for other purposes.

Having thus fully described my invention, I claim as new and desire to secure by Letters Patent—

75 1. A burner having a mixing-chamber provided with a vertical and a horizontal member, the vertical member being open at its lower end to the atmosphere and having a gas-inlet, a burner-tip connected with the top 80 of said mixing-chamber, a heating or combustion chamber surrounding the burner-tip and having air-inlets separate from the air-inlets of the mixing-chamber, and means for supporting the mixing-chamber from the heating-chamber and holding the same in contact therewith, as set forth.

2. A burner having a mixing-chamber provided with air and gas inlets and having a vertical and a horizontal member, a burner-tip 90 connected with said mixing-chamber, a heating or combustion chamber surrounding the burner-tip and having air-inlets separate from the air-inlets of the mixing-chamber, and an auxiliary tip connected with the horizontal 95 member of said mixing-chamber and extending in the heating or combustion chamber, as set forth.

3. A burner having a mixing-chamber provided with air and gas inlets and formed with 100 a vertical member and a horizontal member, a burner-tip connected with said mixing-chamber, a heating or combustion chamber surrounding the burner-tip and having air-inlets separate from the air-inlets of the mixing-chamber, and an auxiliary tip connected with the top of the horizontal member of said 105 mixing-chamber and extending in the combustion-chamber, the upper end of said auxiliary tip reaching to the outlet of the combustion-chamber, as set forth.

4. The combination with a burner having a mixing-chamber provided with air and gas inlets, and a burner-tip connected with the top of the mixing-chamber and formed with 115 a depending flange provided with notches, of a heating or combustion chamber surrounding the burner-tip, and having air-inlets separate from the air-inlets of the mixing-chamber, and a receptacle for the material to be 120 heated, the said receptacle forming the top of the heating or combustion chamber, as set forth.

5. The combination with a burner having a mixing-chamber provided with air and gas 125 inlets, and a burner-tip connected with said mixing-chamber, of a heating or combustion chamber surrounding the burner-tip and having air-inlets separate from the air-inlets of the mixing-chamber, and a receptacle for the material to be heated, said top plate having 130 an annular upwardly-extending rim for di-

rect engagement with the bottom of the heating-chamber, the top plate also having a flange depending from the under side and within which extends the upper end of the

5 mixing-chamber, as set forth.

6. A burner having a top plate provided with a rim, a heating or combustion chamber against the bottom of which the rim of the top plate is adapted to engage, and a spring 10 having its ends extending upward and engaging respectively the heating-chamber and the top plate of the burner for supporting the latter and holding the rim in contact with the under side of the heating-chamber, as set forth.

15 7. A burner having a mixing-chamber provided with an air-inlet and connected with a gas-supply, a top plate for said mixing-chamber and extending beyond the same, the top 20 plate having a depending flange adapted to receive the upper end of the mixing-chamber, the extended portion of the top plate having air-inlet openings, and a burner-tip on the upper surface of the top plate and connected with said mixing-chamber the said 25 burner-tip fitting within a correspondingly-shaped flange on the top plate, as set forth.

8. A burner, comprising a heating or combustion chamber, having an opening therein, 30 an apertured top plate having a rim fitting the under side of the heating-chamber around the opening, the said top plate having a depending flange on its under face, a burner-tip on the upper surface of the top plate, and a 35 mixing-chamber having a vertical member open at its lower end to the atmosphere and provided with a gas-inlet and a horizontal member extending from the upper portion of the vertical member, the said mixing-chamber 40 being connected with the burner-tip by apertures in the top plate, the upper end of the mixing-chamber fitting within the depending flange on the top plate, as set forth.

9. The combination with a heating or combustion chamber having an opening in its bottom, of a burner having a top plate carrying a burner-tip and provided with a rim fitting the under side of the heating-chamber around the opening, and springs engaging 45 lugs on the burner and the heating-chamber for connecting the burner with said heating-chamber and for holding the rim of the top plate in firm contact with the under side of the heating-chamber, as set forth.

50 10. The combination with a heating-chamber provided in its under side with depending lugs, of a burner having a top plate arranged to engage the under side of the heat-

ing-chamber, the top plate being also provided with depending lugs, and springs engaging the lugs of the heating-chamber and the said top plate, as set forth.

55 11. The combination with a heating-chamber, of a burner engaging the under side of the heating-chamber, and a bent spring coiled 60 at the bend and having its members extending upward and connected respectively with the heating-chamber and the burner to hold the burner against the heating-chamber, as set forth.

12. The combination with a heating-chamber provided on its under face with depending lugs, of a burner on the under side of the heating-chamber and also provided with lugs 65 in horizontal alinement with the lugs on the heating-chamber, and springs engaging the lugs to hold the burner against the heating-chamber, as set forth.

13. A burner, comprising a mixing-chamber having a vertical member open at its lower 70 end to the atmosphere, and provided near said lower end with a gas-inlet extending upward and inward through the wall of said vertical member, a top plate for said mixing-chamber provided with an upwardly-extending 75 rim, and a burner-tip on the top plate within said rim and connected with the mixing-chamber, the said burner-tip having a depending flange provided with notches and engaging a correspondingly-shaped flange on 80 the top plate, as set forth.

14. A burner, comprising a mixing-chamber having a vertical member and an approximately horizontal member, the vertical member being open at its lower end to the atmosphere, and provided near said lower end with a gas-inlet adapted for connection with a gas-supply pipe, a top plate for the mixing-chamber and extending beyond the same, the top 95 plate having an integral depending flange 100 adapted to receive the upper end of the mixing-chamber, a burner-tip on the top plate and connected by apertures in the top plate with the mixing-chamber, the extended portion of said top plate being also provided with 105 apertures, and an upwardly-extending auxiliary tip connected with the horizontal member of the mixing-chamber near the end thereof, as set forth.

In testimony whereof I have signed my 110 name to this specification in the presence of two subscribing witnesses.
